Primary Examiner—Joel Sincavage
Attorney, Agent, or Firm—Barbara R. Doutre[57] **CLAIM**

The ornamental design for a battery housing for a portable communication device, as shown and described.

DESCRIPTION

FIG. 1 is a front elevational view of a battery housing for a portable communication device in accordance with our new design;

FIG. 2 is a right side elevational view thereof;

FIG. 3 is a left side elevational view thereof;

FIG. 4 is a rear elevational view thereof;

FIG. 5 is a top plan view thereof;

FIG. 6 is a bottom plan view thereof;

FIG. 7 is a bottom, rear, and right side perspective view thereof;

FIG. 8 is a front elevational view of an alternative embodiment of the same inventive concept shown in FIGS. 1-7;

FIG. 9 is a right side elevational view of said alternative embodiment shown in FIG. 8;

FIG. 10 is a left side elevational view of said alternative embodiment shown in FIG. 8;

FIG. 11 is a rear elevational view of said alternative embodiment shown in FIG. 8;

FIG. 12 is a top plan view of said alternative embodiment shown in FIG. 8;

FIG. 13 is a bottom plan view of said alternative embodiment shown in FIG. 8; and,

FIG. 14 is a bottom, rear, and right side perspective view of said alternative embodiment shown in FIG. 8.
